Primary Examiner — Khawaja Anwar*Assistant Examiner* — Julice Seung Eun Oum(74) *Attorney, Agent, or Firm* — Dickinson Wright,
PLLC; Stephen A. Mason; Jonathan H. Harder**CLAIM**

The ornamental design for a rehabilitation device, substantially as shown and described.

DESCRIPTION

FIG. 1 is a top isometric view of a rehabilitation device.

FIG. 2 is a front view of the device of FIG. 1.

FIG. 3 is a rear view of the device of FIG. 1.

FIG. 4 is right side view of the device of FIG. 1.

FIG. 5 is a left side view of the device of FIG. 1; and,
FIG. 6 is a top view of the device of FIG. 1.

The dashed lines form no part of the claimed design.
